John G. Sparkes

UNITED STATES PATENT OFFICE

2,011,660

HINGED BOX

John Gordon Sparkes, Great Neck, N. Y.

Application October 18, 1933, Serial No. 694,182
Renewed January 14, 1935

3 Claims. (Cl. 132—83)

This invention relates to the construction of cosmetic boxes, and in particular to an unique detail in the hinging of the cover of the box. This detail represents a substantial part of the 5 cost of producing a satisfactory box and many types of hinge have been designed for this purpose. Most of these hinges are composed of small intricate parts which require skillful assembly operations.

10 A minimum of five pieces is generally used to produce a vanity box of simple design. These parts are the box, cover, mirror, hinge pin, and bezel.

This design contemplates the formation of the 15 hinge pin as an integral part of the mirror, if a metal mirror is used, or of the bezel if a glass mirror is used. This detail produces a very satisfactory box at a greatly reduced cost, both for materials and assembly labor; and further reduces the box to a three piece unit in the case of the metal mirror, and only uses four pieces if the 20 glass mirror is used.

Besides the economy of manufacture, a very 25 much more substantial box is produced by this construction.

In order to more clearly describe the invention reference is made to the accompanying drawing which forms a part of this specification and in which,

30 Fig. 1 is a plan view of a substantially round vanity box with this hinge construction.

Fig. 2 is a section taken on the line 2—2 of Fig. 1.

Fig. 3 is a vertical section, similar to Fig. 2 but showing a modification for the use of a glass mirror.

Fig. 4 is a rear elevation of the box showing the method of making the hinge bearing.

Fig. 5 is a plan view of the mirror removed 40 from the cover.

Fig. 6 is a rear elevation of the box cover.

Fig. 7 is a plan view of the bezel with hinge pin used in the assembly shown in Fig. 3.

Fig. 8 is a plan view showing the hinge design 45 applied to a rectangular box.

Fig. 9 is a vertical section taken on the line 9—9 in Fig. 8.

In the drawing a vanity box with a bottom 1, has side walls 2 drawn integral therewith. A tab 3 is extended from the side wall 2 of the box to form a hinge bearing 4 when rolled backward as shown in Fig. 2. A mirror 5 preferably of polished metal has an extension 6 projecting therefrom, this extension has a slot 7 pierced therein to form the hinge pin 8. This hinge pin of

course runs parallel to a tangent to the box, as shown in Fig. 1. The hinge pin may be swaged to make it round if desired. A box cover 9 of shape the same as the box but of a size suitable to fit into the box, has downturned side walls 10 and a slot 11 pierced therein adapted to receive the extension 6 of the mirror 5. When the mirror is assembled into the cover, with extension 6 projecting through slot 11 and the mirror set firmly against the cover 9, the side wall 10 is shaped inward to engage the edge of the mirror and clinch it in the cover. The cover being tightly clinched to the mirror it is ready to assemble to the box. The tab 3 formed on the side wall 2 of the box is threaded through the slot 7 of the extension 6; and is then curled around the hinge pin 8 while it is in place. This forms the hinge connecting the box, cover and mirror permanently together. The cover 9 then enters the side wall 2 of the box and is stopped at proper level by stop 12, formed by lancing a small projection outward, preferably directly opposite the hinge. In order to clear the hinge connection properly notches 13 are provided at each end of the hinge bearing 4, as shown in Fig. 4.

When a glass mirror 5a is used, it is placed in the cover 9, just as the metal mirror described, but to retain it in place a bezel 15 is used and is clinched in by the edge of the cover as before. The extension 16 is provided on the bezel and is constructed exactly as the extension 6 described. The cover enters the box and is stopped by the projection 12 as before.

The Figures 8 and 9 show the same construction applied to a rectangular box.

Obviously this same hinging principle may be applied to boxes of varied design, and for various uses without departing from the scope and purpose of this invention.

Furthermore a plate may be used instead of the metal mirror or bezel as described to effect the same hinge construction for boxes requiring no mirror.

Having described my invention what I claim as new and desire to secure by Letters Patent is:

1. A covered box comprising a compartment with upturned side walls, a cover with downturned edge, an aperture in said edge, a plate shaped to fit into said cover and to be firmly engaged thereby, an extension from said plate projecting through said aperture, a hinge pin formed in the said extension, a hinge bearing formed from the side walls of said compartment and adapted to engage and bear on said hinge pin, substantially as described.

2. A covered box comprising a compartment with upturned side walls, a cover with down-turned edge, an aperture in said edge, a metal mirror shaped to fit into said cover and to be firmly engaged thereby, an extension from said mirror projecting through said aperture, a hinge pin formed in the said extension, a hinge bearing formed from the side wall of said compartment and adapted to engage and bear on said hinge pin, substantially as described.
5. A covered box comprising a compartment
10. A covered box comprising a compartment

with upturned side walls, a cover with down-turned edge, an aperture in the said edge, a mirror set in said cover, a bezel to retain the mirror, shaped to fit into said cover and adapted to be firmly engaged thereby, an extension from said bezel projecting through said aperture, a hinge pin formed in the said extension, a hinge bearing formed from the side wall of the said compartment and adapted to engage and bear on the hinge pin, substantially as described.

JOHN GORDON SPARKES.
